UNITED STATES PATENT OFFICE

2,440,964

SURGICAL SPLINT

Harry G. McCarty, Martin, Ky.

Application September 16, 1944, Serial No. 554,440

1 Claim. (Cl. 128—87)

1

The present invention relates to new and useful improvements in surgical splints, and has for its primary object to provide, in a manner as hereinafter set forth, an appliance of this character which is adapted to be expeditiously and accurately adjusted to meet various conditions.

Another very important object of the invention is to provide an adjustable surgical splint of the aforementioned character comprising novel traction means.

Other objects of the invention are to provide a surgical splint of the character described which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a back splint constructed in accordance with the present invention.

Figure 2 is a cross sectional view, taken substantially on the line 2—2 of Figure 1.

Figure 3 is a bottom plan view of one of the cross members of the back splint with an end portion thereof broken away.

Figure 4 is a top plan view of an arm splint assembly.

Figure 5 is a view in side elevation of the arm splint.

Figure 6 is a bottom plan view of the angularly adjustable member of the arm splint.

Figure 7 is a cross sectional view, taken substantially on the line 7—7 of Figure 4.

Figure 8 is a top plan view, showing the traction device mounted on the splint, with a portion thereof in section.

Figure 9 is a view in side elevation thereof.

Figure 10 is a cross sectional view, taken substantially on the line 10—10 of Figure 8.

Referring now to the drawing in detail, and to Figures 1, 2 and 3 thereof in particular, it will be seen that reference numeral 1 designates generally a pair of spaced, parallel, longitudinally extensible members of suitable material. The members 1 include telescopic male and female sections 2 and 3, respectively. As best seen in Figure 2 of the drawing, the female sections 3 comprise side walls 4 having inturned marginal flanges 5 constituting guides for the male sections

2

2, said male sections being in the form of flat bars.

The members 1 are rigidly but adjustably and detachably secured together in spaced parallelism by means including a plurality of cross bars 6. The male and female sections 2 and 3 have formed longitudinally therein parallel series of openings 7 which are adapted to be brought into registry. Bolts 8 are engageable in the registering openings 7 for securing the male and female sections 2 and 3 in adjusted position. The bolts 8 are provided with wing nuts 9. The cross bars 6 are also provided with openings 10 which are adapted to be brought selectively into registry with the openings 7. The intermediate cross bar 6 is secured in position on the members 1 by the same bolts which connect the male and female sections 2 and 3. Additional bolts are provided for securing the other cross bars 6 in position. The lower faces of the cross bars 6 are recessed, as at 11, to accommodate the wing nuts 9. Handles 12 are provided on the ends of the cross bars 6.

It will thus be seen that a back splint has been provided which may be expeditiously assembled, adjusted as desired, and disassembled. For other purposes than that of a back splint, but one of the members 1 may be used with or without the cross bars 6 or, if desired, either of the male or female sections 2 or 3 may be used alone. The arrangement of the openings 7 and 10 is such as to permit virtually any desired adjustment to be expeditiously had.

In Figures 4, 5 and 6 of the drawing, reference character 13 designates generally an adjustable splint which is primarily for use on an arm. The splint 13 comprises a female member 14, the major portion of which is substantially similar in cross sectional shape to the sections 3. At one end, the female member 14 terminates in spaced, opposed upper and lower plates 15 having openings 16 in their longitudinal marginal portions. The other end portion of the female member 14 slidably receives for longitudinal adjustment a male member 17. The male member 17 has formed therein parallel series of spaced openings 18 for the reception of a pair of securing bolts 19 in the adjacent end portion of the female member 14.

The plates 15 receive therebetween an angularly projecting arm 20. The arm 20 has formed in its inner end portion a multiplicity of openings 21 which are to be brought into registry with either pair of the openings 16 in the plates 15, the arrangement of said openings 21 being such

as to permit substantially any angularity of said arm 20 relative to the female member 14. Bolts 22 secure the arm 20 in adjusted position on the female member 14. The openings 16 in both of the longitudinal marginal portions of the plates 15 permit the arm 20 to be reversed when the splint 13 is to be applied to right or left arms.

The outer portion of the arm 20 is substantially similar in cross sectional shape to the female members 3 and is adapted to slidably receive a male member 23 in the form of an extension. The extension 23 has formed therein longitudinal series of openings 24 in which bolts 25 in the outer portion of the arm 20 are selectively insertible for securing said extension in adjusted position.

The splint 13, after the desired assembly and adjustments have been made, is to be applied to the arm or other member in the usual manner. The various members comprising the splint 13 may be used separately or in combination for various purposes.

In Figures 8, 9 and 10 of the drawing, there is illustrated a traction device 26 applied to one end portion of one of the members 1. The traction device 26 comprises a pair of substantially channel-shaped ratchet bars 27 which are mounted on the longitudinal marginal portions of one of the female sections 3 on one end portion thereof. Toward this end, the ratchet bars 27 have mounted vertically in their inner end portions, slideable spring actuated bolts 28 which are engageable in openings provided therefor in the member 3. The outer ends of the ratchet bars 27 are joined by a telescopic connection 29. It will thus be seen that the ratchet bars 27 are adapted to be mounted on splints of different widths. A coil spring 30 is connected to the outer end portions of the ratchet bars 27 for retaining said ratchet bars in position on the longitudinal marginal portions of the member 3.

The traction device 26 further includes a pair of slideable bars 31 which are operable longitudinally on the ratchet bars 27. The bars 31 include flanges 32 which are slideable in grooves 33 in the flanges of the ratchet bars 27. Thus, the bars 31 are mounted for longitudinal adjustment on the ratchet bars 27. Levers 34 are mounted on the bars 31 for engagement with the ratchet bars 27 for shifting said bars 31. Spring pressed latches 35 are slidably mounted in the bars 31 for engagement with the ratchet bars 27 for releasably securing said bars 31 in adjusted position.

Forwardly projecting links or the like 36 are pivotally connected at one end and have their other ends pivotally connected to the forward end portions of the slideable bars 31, as at 37. Rising from the pivotally connected ends of the links 36 is a hook 38.

In the operation of the traction device 26, the bandage from the limb of the patient being treated is connected to the upstanding hook 38. The slideable bars 31 are then adjusted outwardly on the ratchet bars 27 through the medium of the levers 34 until the desired traction is had. Of course, the spring pressed latches 35 engage the ratchet bars 27 in a manner to releasably secure the slideable bars 31 in adjusted position.

It is believed that the many advantages of a surgical splint constructed in accordance with the present invention will be readily understood, and although preferred embodiments are as illustrated and described, it is to be understood that further modifications and changes in the details of construction may be resorted to which will fall within the scope of the invention as claimed.

What is claimed is:

A surgical splint of the character described comprising a plurality of spaced, parallel members, said members including telescopic male and female sections, cross bars traversing the members at longitudinally spaced points, said cross bars and the sections having openings therein for registry with each other, bolts engaged in the registering openings for adjustably securing the sections and the cross bars together, certain of said bolts further securing the sections in adjusted position relative to each other, and handles on the ends of the cross bars.

HARRY G. McCARTY.
